EnglandApplication May 12, 1933, Serial No. 670,646
In Great Britain April 1, 1933

11 Claims. (Cl. 273—35)

This invention relates to appliances for use in practicing or playing games. Several forms of golf practicing appliances are known and in one of these prior arrangements a golf ball was connected by a length of cord or the like to a length of rubber the latter being for the purpose of returning the ball to the player after the ball had been struck. This prior proposal is not, however, a satisfactory arrangement since there is a 5 possibility on rebound of the ball of the latter striking the player.

One of the objects of the invention is to provide an appliance for use in practicing or playing games in which a golf or equivalent ball is attached to a length of inelastic material such as cord or string and an elastic controlling device is provided so disposed as to return the ball to the player but not to a position beyond that determined by the effective length of the inelastic 10 material.

The invention consists in the novel features of construction hereinafter set out in the appended claims.

In order that the said invention may be clearly understood and readily carried into effect the same will now be more fully described with reference to the accompanying drawing, in which:—

Figure 1 is a perspective view of one form of the invention for use as a golf practicing appliance; and

Figure 2 is a further form of the invention.

In Figure 1 the reference numeral 3 indicates a golf ball having a staple 4 to which is attached a length of inelastic material 5 such as cord or string. The end of the inelastic material 5 remote from the ball 3 is adapted to be anchored to the ground for which purpose a stake or staple 6 is provided. The stake 6 has a piece or strip of leather or similar material 7 which is looped around the stake 6 the end of the cord 5 being threaded as shown through four holes disposed in the contacting ends of the leather strip 7. This arrangement provides a secure attachment for the end of the cord 5 whilst at the same time permitting the active length of the cord to be varied according to requirements. The elastic controlling device as shown comprises a length of elastic material 8 such as rubber connected to and extending transversely to the cord 5 and disposed intermediate the ball 3 and the anchored end of the cord. The ends of the elastic material 8 are anchored by means of stakes 9 each stake being provided with a piece or strip of leather or similar material 10. The free ends of the elastic material 8 are threaded through holes in the

strips 10 to enable the active length of elastic material 8 to be varied and to provide a secure connection between the ends of the elastic material and the stakes 9. The elastic material 8 is connected to the cord 5 by means of a device comprising a loop 11 surrounding the elastic material 8 and another loop 12 arranged at right angles to the loop 11 and surrounding the cord 5.

When using the appliance the flexible inelastic material or cord 5 is taut and lies along the ground 10 and when the ball 3 is hit in the direction of the anchored end of the cord 5 some proportion of the inertia of the struck ball is dissipated in lifting the cord 5 and when the ball passes the point of connection of the cord 5 to the elastic material 15 8 the remaining inertia of the ball is expended in tensioning the elastic material 8 which serves to return the ball to its original position. It will be appreciated that the ball cannot be returned beyond the position determined by the effective 20 length of the cord 5; thus assuming that the ball is hit from the position in which the cord 5 is taut as shown in Figure 1 the ball cannot return to a position beyond that from which it was hit thereby eliminating the possibility of the ball 25 in its return striking the player. The position to which the ball is returned after being struck indicates whether the ball has been cleanly hit or whether it has been "sliced", "pulled" or "foozled". If desired the appliance may be associated with means for indicating the length of drive. For this purpose a strip of flexible material such as tape 11^b may be arranged to lie beneath the cord 5 between elastic material 8 and the stake 6. The tape 11^b is graduated as shown 30 35 and a slidably arranged bead or ball 11^a is arranged on the cord 5. When the ball is struck the cord 5 is lifted and the bead 11^a travels along the cord to an extent depending on the force of drive.

Instead of staking the ends of the elastic material 8 and the end of the cord 5 these ends may be attached to weights to enable the appliance to be used where it is not possible to drive in stakes.

Instead of using stakes or weights as afore-45 said the cord and the rubber strip 8 may be connected to a wooden frame or a frame made of other suitable material; such an arrangement is disclosed in Figure 2. The frame as shown comprises three arms 13, 14 and 15. The 50 cord 5 is attached to the end of the arm 15 at the point 16 and the length of rubber or the like 8 is connected between the two arms 13 and 14 at the points 17 and 18 respectively. The cord 5 as shown lies along the length of the arm 15 55

the three arms being arranged at 120° relatively to each other. The arms 13, 14, and 15 are mounted between a pair of plates 19 and the arms 13 and 14 are pivoted on pins 13a and 14a so as to be capable of being rotated relatively to the plates 19 so as to permit the two arms 13 and 14 to lie against the arm 15 to enable the frame to occupy a minimum amount of space when not required for use and preferably to enable it to be packed in a golf bag. In the example shown, the arm 15 is calibrated and the cord 5 is associated with a bead or ball 11a for indicating the length of drive.

Although the invention has been described above as applied to a golf practicing appliance it is to be understood that the invention may be applied to games or to other practicing appliances such as those employed for practicing tennis.

20 What we claim and desire to secure by Letters Patent of the United States is:—

1. An appliance for practicing or playing games comprising a ball attached to one end of a length of cord, the other end of which is provided with means for anchoring it to a fixed point, a length of rubber connected to and arranged transversely to the said cord and intermediate the ends thereof and means for anchoring the ends of the said length of rubber.

30 2. An appliance for practicing or playing games as in claim 1, wherein the ends of the length of rubber are connected to the means for anchoring the said ends through the medium of strips of material each strip having a plurality of apertures through which the ends of said length of rubber are threaded.

3. An appliance for practicing or playing games comprising a frame having three arms, a ball attached to one end of a length of inelastic material the other end of which is attached to one arm of the said frame, a length of elastic material connected to and extending transversely of the said inelastic material the ends of the elastic material being connected to the two other arms of the frame.

45 4. An appliance for practicing or playing games as in claim 3, wherein the said arms are hingedly connected together to enable the frame to be collapsed.

50 5. An appliance for practicing or playing games comprising a ball attached to one end of a length of flexible inelastic material the other end of which in use is anchored to a fixed point and an elastic controlling device connected to and extending transversely and intermediate the

ends of the inelastic material the elastic controlling device being tensioned when the ball is struck and serves to return the ball to the player but not to a position beyond that determined by the effective length of the inelastic material. 5

6. A golf practicing appliance comprising a golf ball attached at one end to a length of flexible inelastic material, means for anchoring the other end of the inelastic material to a fixed point, an elastic controlling device attached to 10 and extending transversely of the inelastic material and intermediate the ends thereof, and means for anchoring the ends of the elastic controlling device, the arrangement being such that when the ball is struck the controlling device is 15 tensioned, the energy imparted to the said controlling device serving to return the ball to the player but not to a position beyond that determined by the effective length of inelastic material. 20

7. An appliance for practicing or playing games as in claim 5, wherein the elastic controlling device comprises a length of elastic material extending transversely to the inelastic material and disposed intermediate the ends thereof the 25 length of the elastic material and the inelastic material being connected together by means which permit the inelastic material to move along the length of elastic material.

8. A golf practicing appliance as in claim 6, 30 wherein the elastic controlling device and the inelastic material are connected together by a device comprising a pair of loops one of the said loops surrounding the said controlling device and the other the inelastic material. 35

9. A golf practicing appliance as in claim 6, wherein means are provided for anchoring purposes and the members connected to the anchoring means are provided with strips of material looped around the said anchoring means with 40 the ends of the strips in contact, the said ends having a series of apertures through which the ends of the members are threaded.

10. A golf practicing appliance as in claim 6, wherein means are provided for indicating the 45 apparent length of the drive.

11. A golf practicing appliance as in claim 6, wherein the length of the inelastic material is provided with a member slidably mounted thereon and a scale is provided in proximity to the 50 said member to indicate the apparent length of drive according to the position of the said member relatively to the said scale.
